United States Patent Office

Des. 188,181
Patented June 14, 1960

188,181

MOTOR VEHICLE

Leonard G. Gallagher, Berkeley, Calif.
(4647 Foothill Blvd., Oakland, Calif.)

Filed Mar. 21, 1958, Ser. No. 50,133

Term of patent 3½ years

(Cl. D14—3)

Fig. 1.

Fig. 2.

Fig. 3.

Fig. 4.

Figure 1 is a side elevational view of a motor vehicle showing my new design;

Figure 2 is a plan view thereof;

Figure 3 is a rear elevational view thereof; and

Figure 4 is a perspective view thereof, taken from the left and to the rear.

The dominant features of my design reside in those portions shown in full lines.

The side not shown is a mirror image of the side shown.

I claim:

The ornamental design for a motor vehicle, as shown and described.
